REFUSE COLLECTING VEHICLE

Herman C. Frentzel, Jr., Shorewood, and Carl G. Novotny, Milwaukee, Wis., assignors to The Heil Co., Milwaukee, Wis., a corporation of Wisconsin

Application June 13, 1938, Serial No. 213,364

8 Claims. (CL. 214—67)

Our invention relates generally to improvements in the art of handling refuse such as ashes and garbage, and relates more specifically to improvements in the construction and operation of vehicles for collecting, transporting and for dumping such refuse.

In general, our invention has for its object the provision of simple, compact and highly efficient means for effecting loading of a refuse transporting vehicle.

It has long been common commercial practice to utilize so-called refuse trucks of various types for collecting snow and other refuse, and for transporting and subsequently depositing the same upon dumps or elsewhere. As shown in Patent No. 983,906, granted February 14, 1911, it has heretofore been proposed to provide a refuse collecting and transporting vehicle wherein an endless conveyor provided with a series of flights, 20 is utilized to remove refuse from a receptacle disposed rearwardly of the vehicle and to elevate the refuse along the tailgate and over the top of the vehicle body, so as to gradually load the body proceeding in a direction away from the tail gate while simultaneously leveling the load. It has also been proposed as shown in Patent No. 945,330, granted January 4, 1910, to attach the receptacle or elevator boot for receiving the refuse preparatory to elevation there- 25 of, directly to the vehicle adjacent the lower rear portion of the tail gate; and it has been found desirable when such a loading boot or hopper is used, to provide some means for preventing abnormal objects admitted with the refuse from jamming between the conveyor and its housing. In Patent No. 1,915,927, granted June 27, 1933, is shown a loading hopper or elevator boot having the lower portion pivotally suspended and held in normal position by means of 30 springs which will permit the pivoted section to swing away from the conveyor in case overloading occurs; and while this assemblage may function to produce the desired results, it is undesirably complicated and introduces danger of injury to attendants and others and loss of time, due to breakage of the springs, and it is also too noisy for night use.

It is therefore a more specific object of our present invention to provide an improved assemblage for loading a refuse truck and for relieving the loading elevator from excessive stress due to admission of abnormal objects with the refuse, which is extremely safe and quiet in operation.

In accordance with our improvement, we provide a fixed path of travel for the elevating and

distributing conveyor at the loading hopper or boot, and we also provide for admission of the successive batches of refuse so that the continuously advancing conveyor flights will remove the material from the bottom of the accumulated batches. In this manner, the refuse will be gradually removed from a rigid hopper without danger of having the travel of the conveyor flights obstructed either by small or large objects admitted with the successive batches, or 10 by an abnormal accumulation of the material; and the elimination of movable hopper sections and springs obviates danger of breakage and provides an extremely rigid, quiet and durable assemblage which can be manufactured at mini- 15 mum cost.

A clear conception of an embodiment of our present invention, and of the mode of constructing and of utilizing refuse collecting vehicles built in accordance with the improvement, may 20 be had by referring to the drawings accompanying and forming a part of this specification wherein like reference characters designate the same or similar parts in the several views.

Fig. 1 is a side elevation of the rear body portion of a refuse collecting and transporting vehicle, having one of our improved loading rigs associated therewith;

Fig. 2 is an enlarged part sectional side elevation of the improved loading hopper or elevator boot;

Fig. 3 is a similarly enlarged part sectional rear view of the loading boot; and

Fig. 4 is a likewise enlarged plan view of the loading rig with one of the closure covers omitted 35 and the other partially omitted.

While our invention has been shown and described herein as being specifically applied to a rearwardly tilttable refuse collecting body having the loading rig associated with the rear tail gate thereof, it is not our intention to thereby unnecessarily restrict the scope, since the novel features may obviously be more generally applied.

Referring to the drawings, the refuse collecting and transporting dump body shown in Fig. 1, is normally supported for transportation and for rearward tilting, upon a truck of conventional design having transporting wheels 8, and these bodies are tilttable for dumping purposes with the 50 aid of hydraulic or other hoisting means, in a well known manner. The particular type of vehicular dump body shown herein, comprises a receptacle 9 having a bottom 10, a top closure 11, and a rear tail gate 12 which is swingable about 55

a pivot 13 at the upper end thereof to permit free delivery of the receptacle contents when the body is tilted rearwardly. The front side portions of the receptacle 9 are provided with inspection doors 14, and an endless conveyor 15 having a series of material transporting buckets or flights 16 is concealed within the top closure 11 and within a rear closure or housing 17 carried by the tail gate 12. The endless conveyor 15 is adapted to be driven from the propelling motor of the vehicle, through gearing 18 coaxing with the upper front tensioning sprocket of the conveyor; and the medial portion of the conveyor 15 coacts with another sprocket disposed concentric with the pivot 13. The lower rear portion 19 of the housing 17 is enlarged and has guide rails 20 therein which are cooperable with the conveyor rollers 21 to cause the lower end portion of the conveyor to traverse a rather large loop shaped path, see Figs. 1 and 2. The opposite sides of the enlarged housing portion 19, are provided with material supply chutes 22 which are directed toward the interior of the conveyor loop as clearly shown in Figs. 2 and 3; and each of the supply chutes 22 may be provided with a hinged cover 23 and with abutments 25 against which receptacles may be applied when delivering batches of refuse into the adjacent chute 22 or hopper. The conveyor is movable in the direction indicated by the arrow in Fig. 1, so that refuse delivered within the conveyor loop will be carried upwardly along the inclined tail gate 12, by the advancing flights 16, and will be delivered into the upper portion of the receptacle 9 proceeding in a direction forwardly away from the tail gate, and the space between the inclined runs or stretches of the conveyor 15 above the tail gate 12 is preferably free from obstruction. The chutes 22 may also be provided with enlarged upper portions 24, besides the covers 23, for the purpose of preventing undesirable spilling of the material being delivered into these chutes.

During normal use of our improved refuse collecting and transporting assemblage, the receptacle 9 will be positioned as shown in Fig. 1 with the tail gate 12 closing the rear end of the body. When it becomes desirable to load the receptacle 9, the conveyor 15 should first be placed in operation to cause the rollers 21 to constantly advance the successive flights 16 along a fixed path and in the direction indicated by the arrow in Fig. 1. The covers 23 may then be opened and material may be deposited into the lower housing portion 19 through the chutes 22. The successive batches of refuse which are thus admitted to the interior of the lower conveyor loop within the housing portion 19, accumulate in the path of the advancing buckets or flights 16 and as these flights proceed beneath the accumulated refuse, they remove layers or slices of the material and carry the same forwardly and upwardly along the inclined tail gate 12 ultimately delivering the refuse into the receptacle 9 over the top of the tail gate. The material thus delivered into the receptacle 9, at first piles up upon the bottom 10, adjacent to the front side of the tail gate 12; and when the pile reaches the top of the receptacle, the subsequent advancing flights 16 level the accumulated refuse and carry their charges forward until the receptacle 9 is finally completely filled. The conveyor 15 may then be stopped, and when the load has been transported to the desired destination, the receptacle 9 may be tilted and the end gate 12 may be swung rearwardly so as to release the load and permit dumping thereof by

gravity. After dumping has been effected, the receptacle 9 and end gate 12 may be returned to normal position ready for the reception of another load.

From the foregoing detailed description, it will be apparent that our present invention provides a simple, compact and durable assemblage for facilitating loading of a vehicle body with refuse or the like with the aid of an endless conveyor. By admitting the material to the elevator loading hopper or boot above the horizontally advancing successive flights 16, material does not accumulate beneath the conveyor and cannot become lodged beneath the flights regardless of the quantity of material admitted and it is therefore unnecessary to provide a releasable boot section for relieving the conveyor due to abnormal loading. The successive flights 16 advancing beneath the accumulated refuse within the housing portion 19 will constantly shear off approximately equal quantities of the material without crushing the particles as with the prior assemblages, and will remove excessively large objects without unduly stressing the conveyor 15. These large objects if admitted through either chute 22, will also pass through the space between the top and bottom stretches of the conveyor above the tail gate 12, which is unobstructed, and the fixed rails 20 will always guide the flights 16 along a definite course or path. The improved assemblage may be rigidly built, and is accessible for loading from the ground at either side, and has proven highly satisfactory in actual use. The assemblage also presents a neat appearance, is extremely quiet in operation, and may obviously be manufactured at moderate cost and is safe in every respect.

It should be understood that it is not desired to limit this invention to the exact details of construction or to the precise mode of use, herein shown and described, for various modifications within the scope of the claims may occur to persons skilled in the art.

We claim:

1. In combination, a vehicle having a tilttable load receiving body and an inclined tilttable tail gate at the delivery end thereof, a conveyor having an endless series of material transporting flights movable over said body and upwardly along said tail gate, fixed supporting rails for the edge portions of said conveyor forming open loops near the lower end of said wall, and means for delivering material through said rail loops on top of said flights while in motion and while travelling toward said inclined tail gate.

2. In combination, a vehicle having a tilttable load receiving body and an inclined tilttable tail gate at the delivery end thereof, an endless conveyor having an endless series of material transporting flights movable over said body and upwardly along said tail gate, fixed supporting and guiding rails for the opposite side edge portions of said conveyor forming open loops near the lower end of said wall, and means for depositing bulk material through said loops and downwardly into the path of said flights while the same are moving toward the lower end of said inclined tail gate.

3. In combination, a vehicle having a tilttable load receiving body provided with an independently tilttable inclined tail gate, an endless conveyor extending over said body and having a portion supported by and tilttable with said tail gate, said conveyor having a series of flights movable upwardly along said tail gate and along said body, open looped fixed side rails support-

ing the lower portion of said conveyor, and means for delivering bulk material through the openings of said looped rails and downwardly into the path of advancement of said flights.

5. In combination, a vehicle having a body provided with an inclined tilttable tail gate, an endless conveyor having a section tilttable with said end gate and provided with flights movable toward and upwardly along said end gate, a 10 loading boot having a horizontal material receiving surface extending toward and rigidly secured to said tail gate and over which said flights are movable, and means for depositing bulk material upon said surface through the path of travel of 15 said flights.

5. In combination, a vehicle having a body provided with an inclined tilttable tail gate, an endless conveyor having a section comprising inclined parallel stretches tilttable with said end 20 gate and an enlarged loop connecting the lower ends of said stretches, said conveyor being provided with flights movable around said loop toward and upwardly along said tail gate, a loading boot having a lower material receiving surface beneath said loop and extending toward 25 said tail gate and along which said flights are movable, and means for depositing bulk material upon said surface through the open sides of said loop and through the path of travel of said 30 flights at the bottom of the conveyor loop.

6. In combination, a vehicle having a body provided with an inclined tilttable tail gate, an endless conveyor having a section comprising inclined parallel stretches tilttable with said end 35 gate and an enlarged loop connecting the lower ends of said stretches, said conveyor being provided with flights movable around said loop toward and upwardly along said tail gate, looped rails for supporting the lower looped portion of 40 said conveyor and being carried by said tail gate, a loading boot having a material receiving sur-

face disposed between said rails beneath said loop and extending toward said tail gate, said flights being movable along said surface and along said tail gate, and means for depositing bulk material through said looped rails and upon 5 said surface and through the path of travel of said flights at the bottom of the conveyor loop.

7. In combination, a vehicle having a body provided with an inclined movable tail gate, an endless conveyor comprising inclined parallel 10 stretches movable with said tail gate and an enlarged loop connecting the lower ends of said stretches, said conveyor being provided with flights adapted to advance around said loop and toward and upwardly along said tail gate, a loading boot having a lower material receiving surface beneath said loop extending toward and carried by said tail gate and along which said flights are movable, and means for depositing bulk material from either side directly upon said 15 surface through the open sides of said loop and through the path of travel of said flights at the bottom of the conveyor loop.

8. In combination, a vehicle having a tilttable body provided with an inclined independently 20 tilttable tail gate, a conveyor having inclined oppositely movable stretches carried by and disposed parallel to said end gate and an enlarged loop connecting the lower ends of said stretches, said conveyor being provided with flights movable 25 along said stretches and around said loop toward and upwardly along said tail gate, and said tail gate having an integral rearwardly projecting lower portion disposed directly beneath said loop, and means for depositing bulk material 30 through the opposite open sides of said loop and downwardly through the lower portion thereof onto said rearwardly projecting tail gate portion.
